UNITED STATES PATENT OFFICE.

GEORGE W. WEBER, OF NEW YORK, N. Y., ASSIGNOR TO AMERICAN CAN COMPANY, OF NEW YORK, N. Y., A CORPORATION OF NEW JERSEY.

PROCESS OF MAKING SEAMLESS-BODY CANS.

984,173.

Specification of Letters Patent. Patented Feb. 14, 1911.

Original application filed July 26, 1907, Serial No. 385,631. Divided and this application filed August 5, 1908. Serial No. 447,041.

To all whom it may concern:

Be it known that I, GEORGE W. WEBER, a citizen of the United States, residing in New York, in the county of New York and 5 State of New York, have invented a new and useful Improvement in Methods or Processes of Making Seamless-Body Cans, of which the following is a specification.

My invention relates to improvements in 10 the method or process of manufacturing seamless body cans.

This application is a division of my original application No. 385,631, filed July 26th, 1907, on drawn or seamless body cans 15 and method of drawing or making same.

Heretofore in the practical manufacture and use of drawn or seamless body cans for sardines and other articles, and which are ordinarily made of a rectangular shape with 20 sharply curved or rounded corners or of an oval shape somewhat sharply curved at the ends, very great difficulty is experienced from the sheet metal in the seaming flange of the body cracking or breaking under the drawing 25 operation or becoming so wrinkled, puckered or roughened, especially at the rounded corners of the rectangular sardine can or the more sharply curved portions of the oval can, as to render it very difficult or 30 impossible to practically secure with requisite certainty, hermetically tight seams by interfolding the seaming flange of the cover with the seaming flange of the body. And further difficulty is also experienced from 35 the fact that the drawing operation tends to thin and fray the tin coating of the tin plate at the upper portion of the can body and thus render the tin plate peculiarly liable to attack from acids or alkalis in the 40 food or other contents of the can. Heretofore attempts have been made to lessen the percentage of leaky cans incident to the cracking, breaking, wrinkling, puckering or 45 roughening of the seaming flange of the body under the drawing operation by applying to the seaming flange of the cover an elastic packing or gasket of rubber, paper, rubber cement and various forms of packing dope and other expedients which add materially to the cost of manufacture and which 50 at best only serve to palliate without removing the cause of the difficulty.

My invention consists in the means I have discovered for practically removing and

overcoming the difficulties and objections 55 heretofore experienced, and by which I am enabled to practically produce cheaply and rapidly drawn or seamless body cans having sharply curved corners or ends if required, and wherein the seaming flanges thereof will 60 be free from cracks, or breaks, wrinkles, puckers or roughnesses, and which when interfolded with the seaming flanges of the covers will form hermetically tight seams, and wherein the tin plate of the body will be at 65 the same time effectually protected from attack of acids or fruit juices in the food products contained in the can or the contents thereof.

I have discovered that by first applying to 70 the sheets of tin plate in the flat from which the bodies of the cans are to be drawn, a coating of lacquer, preferably the ordinary gold lacquer of commerce, and then baking the coated sheets of tin plate at a temperature 75 preferably of from three hundred and fifty to five hundred degrees Fahrenheit for a period preferably of from one to five hours, and then cutting and drawing the can bodies from such baked lacquered sheets of tin 80 plate, the drawing operation will not only be greatly facilitated, but substantially all liability for the stock to crack or break or to become wrinkled, puckered or roughened at 85 the upper portion of the can body or at the seaming flange thereof will be removed or eliminated, and that at the same time, the drawn can body will be left with a continuous uncracked, unbroken protective coating of 90 baked lacquer over its entire interior surface including the upper surface of its seaming flange, and that this protective coating of baked lacquer will also serve to prevent the tin coating itself underneath from becoming frayed or the iron or steel plate beneath the 95 tin coating from becoming denuded of tin and exposed in streaks, and that the baked lacquer coating will also not only serve to protect the tin plate from attack of acids or alkalis in the contents of the can but also 100 serve as an efficient packing for the folded seam uniting the cover to the can body. The covers are preferably also cut and formed from sheets of tin plate having a similar baked lacquer protective coating. 105 The protective coating on the under surface of the seaming flange of the cover in connection with the protective coating on the

upper surface of the seaming flange of the body thus affords a double packing for the interfolded seam which unites the cover to the body.

5 In the accompanying drawing forming a part of this specification, Figure 1 represents a sheet of tin plate in the flat before it is coated with lacquer. Fig. 2 is a similar view showing the sheet after it is coated 10 with gold lacquer. Fig. 3 illustrates the sheet after the lacquer coating has been baked at a temperature of from three hundred to five hundred degrees Fahrenheit, preferably for two or three hours. Fig. 4 is 15 a perspective view illustrating the body of a seamless or drawn sardine can formed from the baked lacquered sheet. Fig. 5 is a similar view showing the cover of the can. Fig. 6 is a vertical section of the completed 20 can after the cover has been seamed thereon. Fig. 7 is an enlarged detail sectional view through the seam uniting the cover to the can. Fig. 8 is an enlarged detail section on line 8—8 of Fig. 6. Fig. 9 is a detail perspective view partly in section showing my 25 invention as applied to an oval can of greater depth than the sardine can represented in Fig. 6.

In the drawing, A represents a sheet of 30 tin plate in the flat having the customary thin coating of tin *a* on both sides. Before the can bodies and covers are cut and drawn from the sheet of tin plate A, it is first furnished with a protective coating C of lacquer, preferably gold lacquer, and subjected 35 to a baking step or operation in a suitable oven, preferably at a temperature of about three hundred and fifty or four hundred degrees Fahrenheit for a period of two or 40 three hours, which baking operation renders the lacquer hard, dry, innocuous, tasteless and free from odor and causes it to be firmly adherent to the tin plate.

B is the seamless can body drawn from 45 the baked lacquered sheet of tin plate A and having at its upper end a laterally projecting seaming flange *b* and furnished in its interior with a protective coating of baked lacquer C which also extends over the 50 upper surface of the seaming flange *b*.

D is the cover, the same having a marginal seaming flange *d* and provided with a baked lacquered preservative coating C on its inner surface extending over the lower 55 face of its seaming flange *d*. The baked lacquer coating C extends continuously and unbrokenly over the entire interior surface of the can body B and upper surface of its seaming flange *b* and the preservative lacquer coating C on the cover D also extends 60 continuously and unbrokenly over the entire inner surface of the cover including its seaming flange *d*.

By reason of the protective baked lacquer 65 coating C on the tin plate A before the same

is cut and drawn into can bodies, the drawing operation has little and no injurious tendency to crack, break, or to materially or injuriously wrinkle, pucker or roughen the upper portion of the can body including 70 its seaming flange and leaves the body and its seaming flange *b* with a continuous unbroken and perfect tin coating *a* throughout and also with a continuous perfect and unbroken protective baked lacquer coating 75 C throughout, any minute puckers that may exist in the sheet steel of the tin plate or in the upper surface of the tin coating thereof being neutralized or taken up by the hard, dry, baked lacquer coating and not imparted to the upper surface thereof to any appreciable or recognizable extent. And the same also applies to the tin coating C of the cover D. And the sharply curved portions 80 *b*¹ of the can body at the corners thereof if it is of rectangular shape, or at the ends thereof if it is of oval or other shape, as shown in Fig. 9, do not cause the seaming flange of the body to crack, break, or to materially or injuriously pucker or wrinkle at 85 such sharply curved portions. After the body is drawn to shape, it is preferably furnished with an externally projecting bead *b*² near its lower end to give the can body as 90 a whole a symmetrical appearance and to afford a shoulder in conjunction with the folded seam uniting the cover with the body to better hold a label in place on the body. After the can bodies and covers have thus 95 been cut and formed from the baked lacquer protective coated sheets of tin plate and the can body has been filled with sardines or other articles, the cover is united thereto by interfolding the seaming flange *d* of the cover with the seaming flange *b* of the body, 100 preferably into a double seam E, the double thickness of protective coating C between the contacting faces of the seaming flanges *b* *d* serving as an efficient packing to 105 form an hermetically tight folded seam E in conjunction with the freedom from cracks, breaks, and substantial freedom from wrinkles, puckers and roughnesses in such 110 seaming flanges due to my improved method of making or drawing the can bodies and 115 covers.

I claim:

1. The method or process of making hermetically tight seamless drawn body cans which will be proof against attack of acids 120 or alkalis in the can contents, consisting in first coating the sheets of tin plate of which the bodies and covers are to be formed with lacquer, then baking the sheets thereby rendering the lacquer fully dry and hard, 125 and firmly adherent, innocuous and tasteless, then cutting and drawing the can bodies and covers therefrom, said hard, dry, baked lacquer coating serving in said drawing step to diminish and neutralize puckers 130.

in the seam flanges of said bodies and covers and then folding the seaming flanges of the bodies and covers together into double seams with the baked lacquer protective coatings 5 of the bodies and covers extending over the interior surface of the bodies and covers and extending over the seaming flanges of the bodies and covers to serve as a packing for the folded seams, substantially as specified.

10 2. The process of making seamless drawn can bodies with an interior protective coating extending over the seaming flange of the body consisting in first coating sheets of tin plate in the flat with lacquer, then baking 15 the sheets and thereby rendering the lacquer fully dry and hard and firmly adherent and then cutting and drawing the same into can bodies having outstanding seam flanges with said coated surface on the inside, said dry, 20 hard, baked lacquer coating serving in the drawing step to diminish and neutralize

drawing puckers in the seam flanges of said can bodies, substantially as specified.

3. The process consisting in first coating sheets of tin plate in the flat with lacquer, 25 then baking the same thereby rendering the lacquer fully dry and hard and firmly adherent and then forming the same into can bodies and covers having seaming flanges with the baked lacquer protective coating 30 extending continuously and unbrokenly over the interior surface thereof, including the seaming flanges, said hard, dry, baked lacquer coating serving in said drawing step to diminish and neutralize puckers in the seam flanges of said bodies and covers, substantially as specified.

GEORGE W. WEBER.
